UNITED STATES PATENT OFFICE

110,261

DESIGN FOR A SERVICE BAR COUNTER

Andrew J. Stephens, Kansas City, Mo.

Application April 4, 1938, Serial No. 76,290

Term of patent 3½ years

To all whom it may concern:

Be it known that I, Andrew J. Stephens, a citizen of the United States, residing at Kansas City, in the county of Jackson and State of Missouri, have invented a new, original, and ornamental Design for a Service Bar Counter, of which the following is a specification, reference being had to the accompanying drawing, forming part thereof.

Figure 1 is a front elevation of a service bar counter showing my new design.

Figure 2 is a section on line 2—2, Figure 1.

I claim:

The ornamental design for a service bar counter, as shown.

ANDREW J. STEPHENS.
